UNITED STATES PATENT OFFICE.

JAMES W. FARRAR, OF BUFFALO, NEW YORK.

DIRECTION-INDICATOR.

1,204,966.

Specification of Letters Patent.

Patented Nov. 14, 1916.

Application filed November 19, 1915. Serial No. 62,359.

To all whom it may concern:

Be it known that I, JAMES W. FARRAR, a citizen of the United States, residing at Buffalo, in the county of Erie and State of New York, have invented certain new and useful Improvements in Direction-Indicators; and I do hereby declare the following to be a full, clear, and exact description of the invention, such as will enable others skilled in the art to which it appertains to make and use the same.

This invention relates to new and useful improvements in direction indicators and is particularly adapted for use on motor vehicles to enable the operator to signal to traffic policemen and vehicles and pedestrians approaching the direction he is desirous of taking.

Another object of the invention is to provide a device which may be readily constructed of sheet or cast metal and which is so arranged as to direct the light through indicating plates so that the direction to be taken may be readily visible after dark.

Still another object of the invention is to provide a device which will take the place of the ordinary tail light and which is so arranged as to shed light on the rear number plate.

With these and other objects in view, the invention consists in the novel combination and arrangement of parts which will be fully set forth in the following specification and accompanying drawings, in which—

Figure 1 is a view illustrating my improved signaling device attached and ready for use. Fig. 2 is a perspective view of the direction indicator. Fig. 3 is a top plan view of the indicator. Fig. 4 is a vertical sectional view through the indicator near one of its ends. Fig. 5 is a sectional view through the indicator at the center. Fig. 6 is a face view of the reflector plate; and Fig. 7 is a detail perspective view of one of the signaling panels.

Referring to the drawings the numeral 1 designates the base or reflector plate of the device which is provided with a central depression 2. Formed at the sides of the central depression are the lateral depressions 3 and these depressions each form reflectors for the light given off by the lamp bulbs 4. The lower edge of the plate is provided near each end with a pair of longitudinally extending slots 5, while the ends are provided with the barrels 6 formed with internally

screw threaded openings 7 at each end. The slots 5 are for the reception of the bolts by which the number plate of the vehicle is attached to the device. The barrels 6 above referred to are adapted to receive the attaching screws of the face plate which will be more fully hereinafter described.

The face plate of the indicator is designated generally by the numeral 8 and comprises a pair of frames 9, which are connected centrally by a thickened portion 10 and carry a suitable frame 11, which also is disposed in such a manner as to connect the frames 9. As shown in the drawings, it will be seen that the thickened portion 10 is formed integral with the upper bar of each of the frames 9 while the lower bars of said frames are not connected, thus leaving a space through which the light passes from the central light bulb down on to the number plate.

Mounted in the circular frame 11 is a suitable lens 12 which is held in place by the resilient ring 13 and an annular shoulder 14 formed in said frame and this lens is preferably red or green so that it may be used in place of the usual rear tail lens of the vehicle or may be placed at the forward end thereof.

The frames 9 are each provided with the glass panels 15 which are held in place by the angle strip 16 and the flanges 17 forming on the frame. The angle plates 16 are held in place in the frame by the screws 18 which are threaded into threaded openings in the frame and are arranged so that they engage the rear edges of the horizontal arms of the angle plates. Each of the panels 15 is preferably of a red glass coated on the rear side with any suitable opaque coating to form the characters 19 which are in the shape of letters so as to form the words "Left" and "Right". It will thus be seen that when the light in one of the frames is lighted, it will indicate either left or right according to the wording on the panels. The lights positioned within the reflectors are retained in place by suitable sockets 20 which in turn are mounted by being attached in the collars 21 formed integral with the reflectors and it will thus be seen that the lights will be held in the proper position to reflect and distribute the lights over the inner sides of the panels.

It will be apparent from the foregoing that in use the device is attached to a vehicle

of the ordinary construction and the lights are connected to a suitable power source and are controlled by a single switch or a plurality of independent switches. The number plate is then attached to the reflector plate 1 and detached therefrom in such a position that the light given off by the center lamp bulb will be directed down against the face of the number plate thereby making the numbers thereon readily visible. It will also be apparent that the central light will shine through the lens 12 and the use of the ordinary type of tail lamp will be eliminated. When the operator is desirous of making a turn either to the right or left the control switch for the signal is thrown to either position and it will be evident that the letters forming the words will appear illuminated while the ground will remain dark. In this way, it will be seen that the signal may readily be given and persons approaching the vehicle can easily determine in what direction the operator will travel.

While in the foregoing there has been shown and described the preferred embodiment of this invention, it is to be understood that such changes may be made in the combination and arrangement of parts as will fall within the spirit and scope of the appended claims.

What is claimed is:—

1. A direction indicator comprising a re-

flector plate, reflectors formed in said plate, lamp bulbs mounted in the reflectors, screw receiving barrels formed at opposite ends of the plate, frames attached to the barrels, screws extending into said barrels to support the frames, direction indicating panels carried by the frame, a central frame and a lens mounted directly over the central lamp and within the central frame to form the rear signal lamp of the vehicle on which the device is used.

2. A direction indicator comprising a reflector plate, reflectors formed in said plate, lamp bulbs mounted in the reflector, barrels formed at opposite ends of the plate, frames attached to the barrels, screws attaching the frames to the barrels, direction indicating panels carried by the frame, a central frame connecting the first mentioned frame and a lens mounted directly over the central lamp and within the central frame, a flange extending below the body of the reflector plates and having slots, said flange being adapted to form an attaching means for the license plates of the vehicle.

In testimony whereof I affix my signature in presence of two witnesses.

JAMES W. FARRAR.
